UNITED STATES PATENT OFFICE.

ALFRED E. HUNT, OF PITTSBURG, PENNSYLVANIA.

ELECTROLYTIC APPARATUS.

SPECIFICATION forming part of Letters Patent No. 582,923, dated May 18, 1897.

Application filed December 4, 1895. Serial No. 571,064. (No model.)

To all whom it may concern:

Be it known that I, ALFRED E. HUNT, of Pittsburgh, in the county of Allegheny and State of Pennsylvania, have invented a new 5 and useful Improvement in Electrolytic Apparatus, of which the following is a full, clear, and exact description.

My invention has been especially devised with reference to the electrolytic production 10 of aluminium from fused baths, and I shall so describe it, particularly premising, however, that it is not limited in scope to such application, but may be applied to other apparatus used for electrolysis or for electrical heating.

15 The invention is illustrated in the accompanying drawings, in which—

Figure 1 shows in side elevation a series 20 of electrolytic pots constructed in accordance with my invention. Fig. 2 is an end elevation showing one of the pots, and Fig. 3 is a detail sectional view.

In the manufacture of aluminium in large 25 establishments using a current of high tension (two hundred and fifty volts or more) applied to the metal-pots, wherein the aluminium is reduced by electrolysis from a solution of alumina in a molten bath and is deposited on the lining of the pots which are directly included in the electric circuit and serve as the 30 cathodes, the workmen who attend the pots and manipulate the anodes are liable to be injured when standing upon wet earth, or when, for any other reason, a good ground connection or direct circuit is established through 35 the workman between the pot at which he is working and the other end of the electric circuit, where the current enters the series of pots. It is for the purpose of avoiding such danger that I have devised my present invention. It consists in placing around each 40 pot and in direct electrical connection therewith a metal platform, preferably constituted by extending the bottom plates of the pot outward laterally beyond the sides of the pot. 45 The workman must stand upon this platform in order to get access to the pot, and as the platform is necessarily at the same electrical potential as the pot itself the current cannot pass through him. He is therefore in a position 50 of safety no matter what be the voltage of the current. Each pot should have its

own platform electrically distinct from the platforms of the other pots.

The details of construction of the apparatus may be modified within wide limits. The 55 metal platform may be constituted by plates integral with the bottom plates of the several pots or by separate plates riveted or otherwise secured to the bottom plates, and other modifications may be made by the skilled 60 mechanic.

In the accompanying drawings, 2 2 are the pots.

3 3 are the carbon anodes, which enter the electrolytic bath and are connected to the 65 conductors 4 by clamps 5, and 4' are standards which support the conductors 4. Each pot has a conductor 6 electrically attached to the metal shell of the pot, so that the carbon lining of the latter shall serve as the cathode. 70 The pots are connected in series by conductors 7 and the arrangement is such that the difference of potential at the end of the series is high, the fall of potential at each pot being comparatively small.

75 8 8 are the platforms for the workmen, these platforms being formed by extending the bottom plates of the pot, as shown in the drawings.

I claim—

1. Electrical apparatus of the character described, having a number of pots or vessels electrically connected in series, and the several pots or vessels having metal platforms in electrical connection therewith, so that they 85 shall be maintained at the same electrical potential as the pot; substantially as described.

2. Electrolytic apparatus of the character described, having a number of pots or vessels electrically connected in series, and the several pots or vessels having metal platforms in electrical connection therewith, so that they 90 shall be maintained at the same electrical potential as the pot, said platforms being constituted by extensions of the bottom plates of 95 the pots; substantially as described.

In testimony whereof I have hereunto set my hand.

ALFRED E. HUNT.
